UNITED STATES PATENT OFFICE.

HERBERT E. MERSELES, OF BRONXVILLE, NEW YORK.

WASHING APPARATUS.

Application filed June 18, 1921. Serial No. 478,492.

To all whom it may concern:

Be it known that I, HERBERT E. MERSELES, a citizen of the United States, residing at Bronxville, in the county of Westchester and State of New York, have invented certain new and useful Improvements in Washing Apparatus, fully described and represented in the following specification and the accompanying drawings, forming a part of the same.

This invention relates to washing apparatus and has for an object to facilitate the placing of the articles to be washed in washing position and the removal of the articles from such position.

The dish racks customarily used in dish washing machines are so heavy, when filled with dishes, that it is difficult to lift them vertically and they may be satisfactorily handled only by sliding them horizontally. It has, therefore, been customary to provide washing machines with side openings through which such racks may be slid onto a fixed support in the chamber in which the washing takes place. Such washing machines have proved objectionable because it has been found impossible, as a practical matter, to provide removable closures for side openings in the washing chamber which will effectively prevent water from leaking out through these side openings during the washing operation.

The present invention aims to do away with the disadvantages inherent in side openings in the washing chamber while at the same time retaining the advantage which was secured by the side openings, that is to say, avoiding any handling of the racks by the attendant other than a simple horizontal sliding of them.

In accordance with the present invention, the washing chamber is in the form of a tank whose only opening is at the top. Within the tank is a movable support and means are provided for moving the support substantially vertically between washing position in the tank and a position at the level of the upper edge of the tank. When the support is in the latter position racks of dishes may be moved onto it from a fixed support outside the tank or moved from it onto the fixed support by a simple horizontal sliding of the racks. The handling is thus as simple as in side door machines, while the leakage inherent in such machines is entirely eliminated, by placing the opening

at the top of the washing chamber and providing a simple closure therefor.

In the form which has been found most desirable, the tank is provided with a hinged cover and with a vertically movable support which is connected with the cover in such a way that when the cover is opened the support is raised to the level of the top of the tank and when the cover is closed the support is lowered within the tank so as to bring the rack into washing position. Table tops or shallow troughs extend from the edge of the top of the tank and provide means from which the racks may be slid upon the support and means upon which the racks may be slid from the support, when the support is in raised position; they serve also to direct any water dripping from the dishes back into the tank.

Other objects and advantages of the invention are set forth in connection with a detailed description of the specific embodiment of the invention shown in the accompanying drawings, in which—

Fig. 1 is a side elevation of the tank, sectioned on the line 1—1 of Fig. 3, showing the cover open and the support in raised position;

Fig. 2 is a view similar to Fig. 1, showing the cover closed and the support in lowered position;

Fig. 3 is a front elevation of the tank sectioned on the line 3—3 of Fig. 1, showing the cover open and the rack in raised position;

Fig. 4 is a front elevation of the complete apparatus showing the cover of the tank in closed position;

Fig. 5 is a top view of the complete apparatus showing the cover of the tank open, the washing mechanism and linkages being omitted for the sake of clearness;

Fig. 6 is a plan view of the rack support;

Fig. 7 is an enlarged section on line 7—7 of Fig. 6;

Fig. 8 is an enlarged section on line 8—8 of Fig. 6; and

Fig. 9 is a view similar to Fig. 5 showing a modified arrangement of the tables.

The tank 10 which may conveniently be made rectangular in form, as shown in the drawings, is open at the top. At the upper edge of the tank 10 are three externally projecting flanges 11, 12 and 13 located at 110 the sides and front of the tank respectively. Located upon opposite sides of the tank 10

are tables 15 and 16, each provided with a flat top 17, 18 (Figs. 4 and 5). The inner edge of the table top 17 is secured to the flange 11 of the tank 10, so as to form a water tight joint therewith, while the outer portion of the table top is supported upon legs 19. The inner edge of the table top 18 is secured to the flange 12 of the tank 10 so as to form a water tight joint therewith while the outer portion is supported upon legs 20. Each of the table tops 17, 18 is provided along each of its sides with a lip 21 so that the table tops form in effect shallow troughs. The table legs 19, 20 are preferably provided with means for adjusting their height as indicated at 22 in Fig. 4 and are most desirably so adjusted that the table tops 17, 18 are both inclined towards the tank 10.

If desired the tables 15 and 16 may be arranged at right angles to each other and their tops 17, 18 secured to the flanges 13 and 12 respectively, as illustrated in Fig. 9.

The tank 10 is provided with washing mechanism 25 adapted to project water or other washing medium against the articles to be washed in the tank. Any suitable form of washing mechanism may be used for this purpose, the particular form of the washing mechanism not being material to the present invention. In the form shown in the drawings, for the sake of illustration, the washing mechanism comprises a washing unit including a rotary spray arm 26 having upwardly directed discharge orifices 27 of which the two end ones are inclined, a pump 28 for drawing water from the tank and forcing it through the spray arms and a motor 29 for driving the pump. No claim is made herein to the washing unit illustrated, as this forms the subject matter of a copending application of Herbert E. Merseles, Henry R. Merseles, Charles F. Simmons and Paul H. Engel, filed May 5, 1921, Serial No. 467,046, and certain features of it form a part of the subject matter of a co-pending application of Herbert E. Merseles and Frank W. Bemm, filed October 9, 1919, Serial No. 329,533.

The tank 10 is provided with a cover 30 which is hinged to the back of the tank. The cover 30 is provided with downwardly projecting flanges 31, 32, 33 at its front and sides respectively, and these flanges lie just inside of the flanges 11, 12, 13 and inside of the inner ends of the table tops secured to these flanges when the cover 30 is closed. The cover 30 is provided with a handle 46.

A vertically movable support 35 is provided for the racks in which the dishes or other articles are to be placed. When the apparatus is provided with the particular washing mechanism illustrated in the drawings or other form of washing mechanism adapted to project the washing medium upwardly in the tank, the support 35 is made

open, that is to say, it contains one or more openings of sufficient extent to permit the washing medium projected upwardly from the washing mechanism to pass through it. In the construction illustrated, the support 35 is in the form of an open frame. Braces 35' extending across the frame of the support, may if desired, be provided. The support 35 is connected to the cover 30 by linkage which includes; a link 36 pivoted at 76 one end to a bracket 37 on the cover and at the other to the support 35 at 38; a link 39 pivoted at one end to a bracket 40 secured to the inside of the back of the tank 10 and at the other end to the support 35 at 41; and a link 42 pivoted at one end to a bracket 43 on the cover and at its other end to an intermediate point 44 of the link 39. The links 36 and 42 are bent or curved so that they do not project above the upper surface of the support 35 when the cover is open (Fig. 1). The links described lie close to one side of the tank 10 while similar links 36', 39', 42' are placed at the other side of the tank.

When the cover 30 is opened to the position indicated in Fig. 1 the support 35 is raised by the links to a position in which its upper surface is on a level with the inner ends of the table tops 17, 18. A stop 45 secured to the inner wall of the tank 10 engages the link 39' to prevent backward movement of the cover and upward movement of the support beyond the position indicated in Fig. 1.

When the cover 30 is closed as shown in Fig. 2, the support 35 is lowered to "washing position," that is, to such a position that the washing medium projected from the washing mechanism will strike the articles carried by the support. The closing movement of the cover is arrested by the engagement of the front flange 31 of the cover with an inwardly projecting flange 47 on the front wall of the tank 10.

It should be noticed that the support 35 is exactly horizontal when in raised position (Fig. 1) and when in washing position (Fig. 2). In intermediate positions the support 35 is substantially horizontal and its motion is substantially vertical.

To facilitate the raising of the support 35 means are provided to counterbalance the weight of the support and the articles placed thereon, as well as the weight of the cover. The counterbalancing means are most desirably placed outside the tank 10. In the form shown in the drawings the counterbalancing means and the connecting mechanism associated therewith comprise the following parts: Short stub shafts 50 are mounted in bearings 51 extending through opposite side walls in the tank 10. To the outer end of each stub shaft 50 is secured an arm 52 to 120

which is attached the upper end of a tension spring 53. The lower end of each spring 53 is adjustably secured to a projection 56 upon the outside of the tank 5 10 by means of a bolt 57 and nut 58. To the inner end of each of the stub shafts 50 is secured an arm 54 which has at its free end an inwardly projecting pin 55 which bears against the lower side of the support 35. The springs 53 tend to draw down 15 the arms 52 and to force up the arms 54, thus counterbalancing the weight of the support, the linkage, and the cover, as well as that of the articles placed upon the support. It should be noted that when the 20 springs 53 are in the position in which they are least extended (Fig. 2) they are substantially perpendicular to the arms 52 and that as the springs become more extended their tension is applied at a more 25 and more acute angle to the arms 52. The springs exert a stronger tension when more extended, but since they pull at a more acute angle to the arms 52 when extended their effective upward force upon the support is substantially the same throughout the movement of the support. By means of the nuts 58, the tension of the springs may be regulated in accordance with the weight 30 of the articles to be placed upon the support 35, so that the cover may be opened and the support raised by a very slight effort.

To aid in properly positioning the racks 35 upon the support 35, the support is provided at its outer edges with upwardly projecting lips 60, 61. The lips 61 at the sides and front of the support are low so that they do not interfere materially with sliding racks onto and off of the support. The lip 60 at the rear edge of the support is preferably made somewhat higher than the lips 61.

In using the washing apparatus described, a rack A is placed upon the table top 17 (Fig. 4) and there filled with soiled dishes or other articles. The cover 30 is opened, bringing the support 35 level with the inner edges of the table tops, and the rack A is slid along the table top 17 between the lips 21 and onto the support 35, and then occupies the position illustrated in Fig. 1. The cover 30 is then closed, causing the support 35 with the rack A upon it to move down to washing position, as illustrated in Fig. 2. The washing mechanism 25 is then operated, projecting water against the articles carried by the support. With the form of washing mechanism illustrated, the water is projected upwardly against the dishes through the open support 35 and the open bottom of the rack. After the dishes have been washed they may be rinsed by means of the washing mechanism 25 or by separate

rinsing sprays not shown in the drawings. When the cleansing has been completed, the cover 30 is opened, raising the support 35 and the rack A, now containing the cleaned dishes, to the position indicated in Fig. 1. The rack is then slid from the support 35 to the table top 18 as indicated in Fig. 5. Another rack containing soiled dishes may then be slid onto the support 35 from the table top 17 before the cover 30 is again closed.

As seen in Fig. 4 the top of the cover 30 is at the same height as the table tops when the cover is closed so that the cover may be used as a continuation of the table tops when the machine is not in operation.

I wish it clearly understood that my invention is by no means limited to the specific embodiments of it described.

What is claimed is:

1. Washing apparatus, comprising the combination of a tank open at the top, a cover for said opening, washing mechanism adapted to direct a washing medium against articles placed in washing position in the tank, a substantially vertically movable support in the tank for articles to be washed, connecting mechanism between the support and the cover adapted to lower the support when the cover is closed and to raise the support to the top of the tank when the cover is opened, means for arresting upward movement of the support when its article-supporting surface is substantially at the level of the top edge of the tank, and means for arresting downward movement of the support when the articles reach washing position.

2. In washing apparatus, the combination of a tank open at the top, washing mechanism adapted to direct a washing medium against articles placed in washing position in the tank, a substantially vertically movable support in the tank for articles to be washed, means for arresting a downward movement of the support when the articles are in washing position, means for raising the support, and means for arresting the upward movement of the support when its article-supporting surface is substantially at the level of the top edge of the tank.

3. Washing apparatus, comprising the combination of a tank open at the top, a hinged cover for said opening, washing mechanism adapted to direct a washing medium against articles placed in washing position in the tank, a movable support in the tank for articles to be washed, and linkage connecting the support and the cover and arranged to maintain the support horizontal in washing position when the cover is closed, to maintain the support horizontal substantially at the level of the top of the tank when the cover is open, and to move the support between said positions when the

cover is moved while maintaining the support always substantially horizontal.

4. In washing apparatus, the combination of a tank containing washing mechanism and open at the top, a hinged cover for said tank, a substantially vertically movable support in the tank for articles to be washed, connecting mechanism between the support and the cover adapted to raise or lower the support when the cover is opened or closed, and means for counterbalancing the weight of the cover, the support and the articles upon the support so as to facilitate the moving of the support by manipulating the cover.

5. In washing apparatus, the combination of a tank open at the top, washing mechanism adapted to direct a washing medium against articles placed in washing position in the tank, a support in the tank for articles to be washed, means for moving said support in a substantially vertical direction between washing position and the top of the tank, counterbalancing means for facilitating such movement, and a stop adapted to arrest upward movement of the support when its article-supporting surface is substantially at the level of the top of the tank.

6. In washing apparatus, the combination of a tank open at the top, washing mechanism adapted to direct a washing medium against articles placed in washing position in the tank, a movable support in the tank for articles to be washed, means for moving said support substantially vertically between washing position and a position substantially at the level of the top of the tank, means located outside the tank for counterbalancing the weight of the support and the articles thereon, and a connection between said support and said counterbalancing means extending through a wall of the tank.

7. Washing apparatus, comprising a rectangular tank open at the top, a cover for said opening, a hinge connecting said cover to the back upper edge of the tank, washing mechanism adapted to direct a washing medium against articles placed in washing position in the tank, a support in the tank having a flat surface to carry a rack containing articles to be washed, a ridge extending around the sides and front of said surface of a height insufficient to obstruct sliding a rack onto said flat surface and a higher ridge extending along the back of said flat surface, means for moving said support substantially vertically in the tank, means for arresting downward movement of the support when the articles in the rack are in washing position, and means for arresting upward movement of the support when its flat surface is substantially at the level of the top of the tank.

8. Washing apparatus, comprising the combination of a tank open at the top, a cover for said opening hinged to the tank at the back upper edge thereof, washing mechanism in the tank, a support having a substantially unobstructed upper surface, and links connecting the cover with the support adapted to raise the support so that its upper surface is at the level of the top of the tank when the cover is opened, said links being so bent that they lie below and behind the upper surface of the support when the cover is open.

In testimony whereof I have hereunto set my hand in the presence of two subscribing witnesses.

HERBERT E. MERSELES.
